UNITED STATES PATENT OFFICE.

ABRAHAM GARBEIL, OF PHILADELPHIA, PENNSYLVANIA.

TOILET-BOX.

1,386,216.

Specification of Letters Patent.

Patented Apr. 6, 1920.

Application filed February 4, 1919. Serial No. 274,917.

To all whom it may concern:

Be it known that I, ABRAHAM GARBEIL, a citizen of the United States, residing at Philadelphia, in the county of Philadelphia and State of Pennsylvania, have invented certain new and useful Improvements in Toilet-Boxes, of which the following is a specification.

One object of my invention is to provide a neat and compact toilet box of the type generally known as vanity boxes and to so construct my improved box that it will conveniently hold, in different compartments, cakes of white or light colored powder and rouge, so that a lady, by a slight movement of certain of the parts, can use either the powder or the rouge.

Another object is to provide my improved box with mirrors which will be so arranged that they may be readily seen when either the powder or the rouge is in position to be used.

A further object is to so construct my improved box that it may be used to hold other toilet articles, such as eyebrow pencil, lip stick and a vial of perfume.

A still further object is to so construct my improved box that it can be readily opened and can be easily carried and manipulated.

These objects, and other advantageous ends which will be described hereinafter, I attain in the following manner, reference being had to the accompanying drawings in which—

Figure 1 is a perspective view of a box made in accordance with my present invention and showing the same in a position in which, for example, the white or light colored powder can be used.

Fig. 2 is a perspective view of the box shown in Fig. 1 in a position permitting the use, for example, of the rouge.

Fig. 3 is a sectional elevation of the box shown in Figs. 1 and 2 and taken on the line 3—3 of Fig. 4.

Fig. 4 is a transverse section taken on the line 4—4 of Fig. 3.

Fig. 5 is a perspective view showing a modified form of my invention.

Fig. 6 is a sectional elevation of the form of my box shown in Fig. 5.

Figs. 7 and 8 are perspective views showing other forms of my improved box.

Fig. 9 is a sectional elevation of the box

shown in Fig. 8 and taken on the line 9—9 of Fig. 10.

Fig. 10 is a transverse section taken on the line 10—10 of Fig. 9.

Fig. 11 is a perspective view showing another modified form of my invention.

Fig. 12 is a central sectional view of the box shown in Fig. 11.

Fig. 13 is a sectional view of another form of box of the same general construction as that shown in Figs. 11 and 12 with the exception that the box is secured by snap-button fasteners; the section being taken on the line 13—13 of Fig. 14, and

Fig. 14 is a transverse section taken on the line 14—14 of Fig. 13.

Referring to the form of my invention shown in Figs. 1 to 4 inclusive, 15 represents the body portion of the box which is open at its top 16 and front end 17. The box can be made of cardboard or other suitable material and is provided with a top cover 18 which is hinged at 19 to the top of the rear of the body portion 15. This cover 18 has a mirror 20 inserted therein and a hinged flap 21 adapted to fold over a front section 22 of the box which is hinged to the bottom edge of the front end 17. The front section 22, when moved into the position as shown in Fig. 3, serves to close the front end 17. The flap 21 and the front section 22 are, respectively, provided with parts of a snap-button 23 whereby the cover 18 closes the top 16 and the parts are locked in their closed positions, as shown in Fig. 3.

Two trays 24 and 25 are positioned within the body portion 15; the tray 24 being hinged at its rear top edge 26 to the back of the body portion 15, so that said tray can be swung on its hinge 26 out of the body portion, for example, from the position shown in Fig. 1 to the position shown in Fig. 2. The bottom of the tray 24 is provided with a mirror 27 so that when the tray is moved into the position, as shown in Fig. 2, the mirror 27 will be exposed to view and the bottom tray 25 will be uncovered. Each of the trays 24 and 25 contains a cake of face powder or rouge, and for clearness of description, it will be considered that the tray 24 contains a cake 28 of compressed white or light colored face powder and the tray 25 contains a cake 29 of colored powder or rouge. In addition, the tray 24 contains a powder puff 30 and the tray 25 contains 110

a similar puff 31. The cakes 28 and 29 are preferably made of such diameter that it requires them to be slightly forced within their respective trays, so that they will not readily become dislodged. However, this feature is optional, for the reason, that when the cover 18 is in its closed or locked position, it is impossible for the cakes or puffs to become dislodged, since they are confined directly to their respective trays, as clearly shown in Fig. 3.

• A rack 32 is secured to the inner surface of the front section 22, said rack including holes 33 in its top through which such articles as eyebrow pencil, lip stick and perfume vial can be inserted; said articles being respectively indicated by the reference numerals 34, 35 and 36.

The trays 24 and 25 are of less width and depth than the body portion 15 so that, when the front section 22 is moved into its upright position to close the front end 17, the rack 32 will assume a vertical position directly in front of the trays 24 and 25 and a space 37 will be left between the side of the trays 24 and 25 and the side 38 of the body portion 15. This space 37 can be used for holding hair pins, safety pins or other small toilet articles.

It will be noted that when the powder 28 is being used, the puff 30 can be employed and the mirror 20 is in a position for use. On the other hand, when it is desired to use the rouge 29, the tray 24 is raised on its hinge into the position shown in Fig. 2 and the mirror 27 on the bottom of the tray 24 can be readily seen and is in proper position for the use of the rouge 29.

The eyebrow pencil, lip stick or perfume vial can be used as desired and can be readily lifted from the rack 32.

The form of my invention shown in Figs. 5 and 6 is substantially the same as that described in Figs. 1 to 4, inclusive, with the exception that the width of the trays is equal to the width of the interior of the body portion of the box, and the rack for holding the eyebrow pencil, lip stick and perfume vial is of less width than that shown in the form of my invention shown in Figs. 1 to 4 inclusive. Therefore, in Figs. 5 and 6, I have given corresponding parts reference numerals similar to those above described.

The form of my invention shown in Fig. 7 is substantially similar to that of Fig. 5 with the exception that, instead of the rack 32, I provide a rack 39 in which the eyebrow pencil 40, perfume vial 41 and lip stick 42 are inserted within the side of the rack instead of through the top. In all other respects, the parts are similar to those described in connection with Figs. 1 to 6, inclusive, and I have given corresponding parts similar reference numerals.

In the form of my invention shown in Figs. 8 to 10, inclusive, the rack is eliminated and the trays occupy the entire space within the body portion. In all other respects, the parts are similar to that described in Figs. 1 to 7, inclusive, and I have, therefore, given corresponding parts similar reference numerals.

In Figs. 11 and 12, I have shown a modified form of my improved box which includes a body portion 43 having a tray 44 secured therein above the bottom so as to provide space for a slidable tray 45. These trays 44 and 45 contain cakes 46 and 47 of powder and rouge and also, respectively, contain puffs 48 and 49. The cover 50 is hinged at 51 to the top edge of the back of the body portion 43 and a front section 52 is hinged at 53 so that it can be moved into the vertical position, as shown in Fig. 10, and thereby form an abutment for the front face of the slidable tray 45. The front edge portion 54 of the front section 52 is of reduced thickness and provides a shoulder 55. The cover 50 is adapted to swing over the portion 54 and abut the shoulder 55, as shown in Fig. 12. Thus the cover 50 serves to both cover the body portion 43 at the top and serves as a retaining means to hold the front section 52 in its upright position. The cover 50 contains a mirror 56 so that by opening the box either the powder 46 or rouge 47 can be used. When it is desired to use the rouge 47, the tray 45 can be slid outwardly in the manner of a drawer and after being used can be slid within the body portion 43. The mirror 56 is in position to be seen while using either the powder or rouge.

Figs. 13 and 14 show a form of my invention substantially similar to that illustrated in Figs. 11 and 12 with the exception that instead of providing the front section with the shoulder for engagement with the top cover, the top cover 57 is provided with a flap 58 of similar construction to the flap 21 above described in connection with Figs. 1 to 4, and the section 59 which is pivoted at its bottom at 60 is provided with a snap-button 61 so that the flap 58 and front section 59 can be secured together. In all other respects, the form of my invention shown in Figs. 13 and 14 is similar to that shown in Figs. 11 and 12, and I have, therefore, given corresponding parts similar reference numerals.

A toilet box made in accordance with my invention, can be made in compact form so that it can be held in an open position in one hand so that the other hand is free for the use of the puffs. In the use of the form of my invention shown, for example, in Figs. 1 to 9, inclusive, the body portion of the box, when open, can be held within the palm of the hand and one thumb can be employed to

hold the upper tray in its raised position when the rouge in the lower tray is being used. Furthermore, my improved box can be readily carried in a small hand bag and 5 can be made of comparatively light weight.

While I have described my invention as taking a particular form, it will be understood that the various parts of my invention may be changed without departing from the 10 spirit thereof, and hence I do not limit myself to the precise construction set forth, but consider that I am at liberty to make such changes and alterations as fairly come within the scope of the appended claims.

Having thus described my invention, what 15 I claim as new and desire to secure by Letters Patent is:

1. A toilet box of the character described including two trays; one of said trays being movably connected whereby it can be moved into a position so as to permit access to the other of said trays; said movably connected tray having a mirror visible when 20 said tray is moved to permit access to the other of said trays; substantially as described.

2. A toilet box of the character described, including two trays mounted one above the other; one of said trays being hinged 30 whereby it can be swung into a position so as to permit access to the other of said trays; said hinged tray having a mirror visible when 35 said tray is moved to uncover the other of said trays; substantially as described.

3. A toilet box of the character described, including a body portion open at its top; a cover for closing said top; a mirror supported on said top; two trays mounted with- 40 in said body portion and positioned one above the other; the upper one of said trays being hinged so as to swing upwardly clear 45 of the other tray and toward said cover; said hinged tray having a mirror on its bottom; substantially as described.

4. A toilet box of the character described, including a body portion open at its top; a cover for closing said top; a mirror supported on said top; two trays mounted with- 50 in said body portion and positioned one above the other; the upper one of said trays being hinged so as to swing clear of the other tray and toward said cover; said hinged tray having a mirror on its bottom; 55 and a front section hinged to the body portion and movable toward and from said trays; substantially as described.

5. A toilet box of the character described, including a body portion open at its top; a 60 cover for closing said top; a mirror supported on said top; two trays mounted within said body portion and positioned one above the other; the upper one of said trays being hinged so as to swing clear of the other

tray and toward said cover; said hinged 65 tray having a mirror on its bottom; a front section hinged to the body portion and movable toward and from said trays; and a rack supported on said front section and adapted to retain various toilet articles; 70 substantially as described.

6. A toilet box of the character described, including a body portion open at its top; a cover for closing said top; a mirror supported on said top; two trays mounted within 75 said body portion and positioned one above the other; the upper one of said trays being hinged so as to swing clear of the other tray and toward said cover; said hinged tray having a mirror on its bottom; and a front section hinged to the body portion and movable toward and from said trays; 80 said trays being of less width than the width of said body portion whereby a storage space is provided in which toilet articles can be carried; substantially as described.

7. A toilet box of the character described, including a body portion open at its top; a cover for closing said top; a mirror supported on said top; two trays mounted within 90 said body portion and positioned one above the other; the upper one of said trays being hinged so as to swing clear of the other tray and toward said cover; said hinged tray having a mirror on its bottom; a front section hinged to the body portion and movable toward and from said trays; 95 and a rack supported on said front section and adapted to retain various toilet articles; said trays being of less width than the width of said body portion whereby a storage space is provided in which toilet articles can be carried; substantially as described.

8. A toilet box of the character described, including a body portion open at its top; a cover for closing said top; a tray mounted within said body; a front section hinged to 100 said body portion and movable toward and from said tray; and means on said front hinged section adapted to hold toilet articles, said body portion providing a space between said tray and front hinged section, whereby when said section is closed said 105 toilet articles will occupy said space within the body portion and when the front section is open the toilet articles will be located outside of said body portion; substantially as described.

In testimony whereof I have signed my name to this specification in the presence of two subscribing witnesses.

ABRAHAM GARBEIL.
